Primary Examiner — Cynthia M Chin(74) Attorney, Agent, or Firm — Woodard, Emhardt, Moriarty, McNett & Henry LLP(57) CLAIM

The ornamental design for a paintball loader feedgate insert, as shown and described.

DESCRIPTION

FIG. 1 is a top view of an insert for a paintball loader feedgate; FIG. 2 is a side view of the insert, the opposite side view being a mirror image of the same; and,

FIG. 3 is a bottom view of the insert.

1 Claim, 3 Drawing SheetsFIG. 1

FIG. 3
